UNITED STATES PATENT OFFICE.

JAMES W. PENFIELD AND RAYMOND C. PENFIELD, OF WILLOUGHBY, OHIO.

BRICK-MACHINE.

SPECIFICATION forming part of Letters Patent No. 426,315, dated April 22, 1890.

Application filed January 13, 1890. Serial No. 336,844. (No model.)

To all whom it may concern:

Be it known that we, JAMES W. PENFIELD and RAYMOND C. PENFIELD, of Willoughby, in the county of Lake and State of Ohio, have 5 invented certain new and useful Improvements in Brick or Tile Machines; and we do hereby declare the following to be a full, clear, and exact description of the invention, such as will enable others skilled in the art to 10 which it pertains to make and use the same.

Our invention relates to improvements in brick or tile machines; and it consists in certain features of construction and combination of parts hereinafter described, and pointed 15 out in the claims.

In the accompanying drawings, Figure 1 is a view in perspective. Fig. 2 is an enlarged elevation in section in detail. Fig. 3 is a plan in detail of pitman *g*. Fig. 4 is an elevation 20 in detail of locking-frame, hereinafter described. Fig. 5 is a view in perspective showing a portion of cross-bar *E*.

A represents an upright cylindrical pugging-box, in which operates the upright pugging-shaft *B*. This shaft is provided in the usual manner with a series of arms *B'*, for tempering the material and forcing the latter downward, and is provided also with a curved arm *B²*, known as a "wiper," adapted to force 25 the material through opening *a* into the compression-chamber *C*, and a vertically-reciprocating plunger or piston *C'* operating in the compression-chamber for forcing the material 30 through grate *C²* into mold *D*, the latter being located directly under the grating and resting on table *D'*. The empty molds are successively placed upon the table at the rearward of the mold being filled, the empty mold, as it is moved forward to a position under the 35 grate, displacing the mold already filled. For thus shifting the mold is provided rock-shaft *d*, having an arm (not shown) that connects with pitman *F*, for actuating the rock-shaft. Shaft *d* is provided with rock-arm *d'*, the latter bearing roller *d²*, this roller being adapted 40 to engage the rear side of the empty mold.

The mechanism thus far described and the co-operating devices for actuating the movable parts are in common use, and are so well 45 known that it is not considered necessary further to describe them, and more especially as

our improvements, hereinafter mentioned, and their relations to other parts of the machine will be readily understood.

Heretofore it was found difficult to supply 55 the compressing-chamber with material, or at least to hold the material in the chamber while piston *C'* was doing its work. To remedy this difficulty we provide as follows: First, the forward section of the bottom plate *A'* 60 of the pugging-box is offset downward, as shown, thus securing a larger opening into the compressing-chamber than would otherwise be had, whereby the material is more readily forced into the chamber. Resting and 65 operating upon the depressed section of plate *A'* is lateral bar *E*, this bar having an intermittently-reciprocating movement forward and back, the rearward position of the bar being shown in solid lines and the forward 70 position of the bar being shown in dotted lines, Fig. 2. While the wiper is sweeping past opening *a* bar *E* remains at rest in its rearward position, and just as the sweeper has passed the orifice bar *E* is advanced to its forward position, thus forcing into the compression-chamber the material that, partly by 75 gravity and partly by the action of the wiper, had been massed in front of bar *E*, the latter maintaining its forward position and holding 80 the material in chamber *C* while piston *C'* is doing its work. With such construction the difficulty aforesaid of supplying chamber *C* with material and holding the material in the chamber while such material is being pressed 85 into the mold is entirely overcome. For actuating bar *E* is provided an oscillating frame, (shown more clearly in Fig. 4,) this frame comprising axial trunnions *G*, side arms *G'*, cross-bar *G²*, and depending wrist *G³*. Shaft *B* 90 extends below the pugging-box, where it is provided with crank *b*, the latter having wrist *b'*, and the two wrists *b'* and *G³* being connected by means of pitman *g*. This pitman is made in two sections or halves bolted 95 together, as shown in Fig. 3, the pitman having a slot *g²*, in which operates wrist *b'*. To and between the prongs of the forward end of the pitman is pivoted box *g³*, the bore of this box fitting wrist *G³*. The upper extremes 100 of arms *G'* are connected, by means of rods *e*, with the extremes of bar *E*, rods *e* extending

loosely through holes in the approximately vertical section of plate A'. The throw of the crank is greater than is required in actuating bar E; hence, slot g³ of the pitman, 5 whereby less than the full throw of the crank is transmitted, and bar E is allowed to remain at rest for a time at either extreme of its throw while the lost motion of wrist b' in slot g³ is being taken up.

10 Heretofore it was found extremely difficult, if not impossible, to prevent the material from being forced into the lower box of the pugging-shaft, the presence of such material in the box causing extra wear, necessitating frequent 15 repairs and an occasional renewal of the parts.

To overcome this difficulty we provide as follows: The lower box H of the pugging-shaft has an upwardly-projecting hub h, and the pugging-shaft is provided directly above the 20 box with collar I, the latter having a depending rim i, that extends down outside hub h, as shown in Fig. 2. This collar is usually shrunk onto the shaft, and hence no material, 25 not even water, can pass between it and the shaft, and material could only enter the box by being forced up between the rim i and the hub h, and this could not occur so long as drip-holes a² are kept open. As a further 30 safeguard hood J is provided, this hood being shaped approximately as shown and inclosing hub h and collar I, the hood being fastened to plate A' and fitting shaft B as close as is practicable. The hub b² of the wiper is chambered to fit over the hood. Plate A' has an 35 upwardly-projecting annular flange a', that is adapted to fit an annular groove b³ of the wiper-hub, and the latter is intended to fit as close as may be to plate A' without actual contact with the plate. Some of the softer 40 material will find its way past rib a' and will become packed in between hood J and the hub of the wiper; but there is not force enough brought to bear on the material to force it down between shaft B and the hood, and a 45 little muddy water is all that reaches thus far, and it is prevented from entering the box by means of the aforesaid collar and depending rim and is readily disposed of through the drip-hole. With such construction there 50 is no difficulty whatever in keeping the material out of the lower box, and hence the wear of this box is reduced to a minimum.

Heretofore the lower front edge of the compression-box or a plate fastened thereto has 55 served to strike off the molds. With such construction it was found extremely difficult, if not impracticable, to secure a compact unbroken smooth top surface on the brick or tile; but, on the contrary, these surfaces were 60 likely to be rough, broken, and fissured. We therefore provide a series of plates c, overlapping each other shingle-fashion, as shown, thus presenting a series of inclined surfaces that successively engage the material in striking off the mold. The front wall of the conveyer-box is chambered, as shown 65 at c', for introducing some lubricant, usually

water, and a series of drip-holes c² are provided, these drip-holes leading from chamber c' and discharging into the recesses had between the different plates c. The first plate c strikes off the mold substantially as heretofore; but between the first and second plate c sufficient lubricant is introduced to slightly soften the surface of the brick and render the 75 material tougher, and hence the second plate c smooths down and compacts the material, and so on, and it is found that with usually three plates c the surface of the brick may be rendered smooth and compact and without a 80 break or fissure in the surface.

What we claim is—

1. In a brick-machine, in combination, an upright pugging-box, a compression-chamber, and a so-called "wiper," adapted to force the 85 material from such pugging-box into such compression-chamber, a cross-bar operating in the pugging-box and located next below the line of the sweeper, such cross-bar having a reciprocating movement toward and from the compression-box, substantially as set forth.

2. In a brick-machine, in combination, upright pugging-box, wiper, compression-box, and cross-bar having an intermittently-reciprocating movement toward and from the compression-box, substantially as indicated, the bottom plate of the pugging-box having an offset or depressed section adapted to accommodate such reciprocating cross-bar below 90 the line of the wiper, substantially as set forth.

3. In a brick-machine, in combination, upright pugging-box and pugging-shaft, a journal-box for the lower end of the pugging-shaft, such journal-box having an upwardly-projecting hub, and a collar rigidly mounted on the pugging-shaft next above the journal-box, such collar having a depending rim adapted to overlap and inclose the upper section of such journal-box, substantially as set forth.

4. In a brick-machine, in combination, upright pugging-box and pugging-shaft, collar mounted on the pugging-shaft, such collar having a depending rim, a journal-box for the pugging-shaft, such journal-box projecting above the bottom plate of the pugging-box into the concavity of such rimmed collar, and a hood fastened to the bottom plate of the pugging-box, such hood being adapted to fit the pugging-shaft and to inclose the flanged collar and adjacent section of the journal-box, substantially as set forth.

5. In a brick-machine, in combination, upright pugging-box and pugging-shaft, upwardly-projecting journal-box and overlapping flanged collar, and hood inclosing such collar and opposing journal-box section, substantially as indicated, and a wiper mounted on the pugging-shaft next above such hood, such wiper having a chambered hub adapted to inclose such hood, substantially as set forth.

6. In a brick-machine, in combination, up-

right pugging-box, pugging-shaft, journal-box, flanged collar, and hood, substantially as indicated, a chambered wiper-hub adapted to inclose such hub, such wiper-hub having 5 an annular groove in the lower face thereof concentric with the pugging-shaft, and an annular rib projecting upward from the bottom plate of the pugging-box, such rib being adapted to operate in the annular groove of the 10 wiper-hub, substantially as set forth.

7. In a brick-machine, the combination, with upright pugging box and shaft, compression-box, wiper, and cross-bar, the latter having reciprocating movement toward and from the

compression-box, substantially as indicated, 15 of a crank mounted on the pugging-shaft, a swinging frame operatively connected with the reciprocating cross-bar, and a slotted pitman connecting such crank and swinging frame, substantially as set forth. 20

In testimony whereof we sign this specification, in the presence of two witnesses, this 4th day of December, 1889.
